DESIGN FOR AN AUTOMATIC SIGN

Fred S. Lewis, South Bend, Ind.

Application July 2, 1936, Serial No. 63,611

Term of patent 3½ years

To all whom it may concern:

Be it known that I, Fred S. Lewis, a citizen of the United States, residing at 822 26th Street, South Bend, in the county of St. Joseph and State of Indiana, have invented a new, original, and ornamental Design for Automatic Signs, of which the following is a specification, reference being had to the accompanying drawing, forming part thereof:

Figure 2 is a view in side elevation of said automatic sign with the portion of Figure 1 illustrated in dotted lines and the flag like panels shown in full lines in said Figure 1 omitted; and

I claim:

The ornamental design for an automatic sign, as shown.

FRED S. LEWIS.
